(57) **CLAIM**

The ornamental design for an ergonomic trolley handle, as shown and described.

DESCRIPTION

FIG. 1 is a first perspective view from the top of an ergonomic trolley handle showing our new design;

FIG. 2 is a bottom perspective view thereof;

FIG. 3 is a first side view thereof;

FIG. 4 is a second side view thereof;

FIG. 5 is a top view thereof;

FIG. 6 is a bottom view thereof;

FIG. 7 is a first end view thereof; and,

FIG. 8 is a second end view thereof.

In the drawings, the broken lines depict portions of the design that form no part of the claim.
